(57) **CLAIM**

The ornamental design for an antenna detection probe for a storage tank, as shown and described.

DESCRIPTION

FIG. 1 is an upper perspective view of the antenna detection probe for a storage tank showing my design with a sensor element extended in an upward position, the probe being positioned on a storage tank with fluid flow in broken lines. FIG. 2 is an exploded perspective view of the probe of FIG. 1, showing the sensor element extended in an upward position, the probe being positioned on a storage tank and with a spring mechanism in broken lines;

FIG. 3 is a side elevation view thereof with the sensor element in a retracted state;

FIG. 4 is an opposite side view thereof with the sensor element in a retracted state;

FIG. 5 is a top plan view thereof with the sensor element in a retracted state;

FIG. 6 is a bottom plan view thereof with the sensor element in a retracted state;

FIG. 7 is a front elevation view thereof with the sensor element in a retracted state;

FIG. 8 is a back elevation view thereof with the sensor element in a retracted state; and,

FIG. 9 is an enlarge bottom perspective view of a tip of the probe, showing a sleeve with a slot opening and the sensor element in a retracted state.

The broken line features are presented for illustrative purposes and form no part of the claimed design.
